(57) **CLAIM**

The ornamental design for a chassis for sunglasses, eyeglasses, or like eyewear, as shown and described.

DESCRIPTION

FIG. 1 is a perspective view of a chassis for sunglasses, eyeglasses, or like eyewear showing my new design;

FIG. 2 is a top plan view thereof;

FIG. 3 is a bottom plan view thereof;

FIG. 4 is a front elevation view thereof;

FIG. 5 is a rear elevation view thereof; and,

FIG. 6 is a left side elevation view thereof, the right side elevation view being a mirror image thereof.

Broken lines shown herein are for illustrative purposes and form no part of the claimed design.
